CLAIM

The ornamental design for a fish hook storage and carrying apparatus as shown and described.

DESCRIPTION

FIG. 1 is a side view of a fish hook storage and carrying apparatus.

FIG. 2 is a reverse side view thereof.

FIG. 3 is an end side view thereof, the reverse side being a mirror image thereof.

FIG. 4 is a top plan view thereof.

FIG. 5 is a bottom plan view thereof.

FIG. 6 is a cross sectional view thereof cut along section line 6-6 of FIG. 1.

FIG. 7 is a cross sectional view thereof cut along section line 7-7 of FIG. 3.

FIG. 8 is a cross sectional view thereof cut along section line 8-8 of FIG. 4.

FIG. 9 is a top side perspective view thereof; and,

FIG. 10 is a top side perspective view thereof.

In the drawings, the broken lines show portions of a fish hook storage and carrying apparatus that form no part of the claim. In FIG. 10, the broken lines also depict environment that forms no part thereof. The fish hook storage and carrying apparatus is shown with a symbolic break in its midsection. The appearance of any portion of the article between the break lines forms no part of the claimed design.
